UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed February 17, 1926. Serial No. 88,793.

The present invention relates to telephone systems in general, but is concerned more particularly with such systems as have special means for informing the operator of the class 5 to which the calling subscriber belongs.

This case may be considered an improvement on the system disclosed in Patent No. 1,281,112, granted to Willis, October 8, 1918. This Willis patent discloses means for 10 alerting the toll recording operator of the class of the calling line by impressing a distinctive tone on the private normal conductor of the calling line, which tone is led over the release trunk conductor when the connection 15 is set up and is placed across the line by means of an induction coil, and is listened to by the operator when she answers the call.

It has been found that the tone on one 20 private normal conductor is very likely to be induced on another private normal conductor, owing to the fact that, since it is a single conductor, the private normal conductor can not be transposed like a two conductor circuit. It has been found 25 also that, to a limited extent, the various tones on the private normal conductors find their way to the talking circuits, thereby giving rise to undesirable noises during conversation. Accordingly, it is an object of the 30 invention to provide a new and improved system in which the tone currents are more nearly confined to their intended paths.

It has been found in practice that the way 35 in which the undesirable transfer of tone current takes place is largely through electrostatic induction from one conductor to another, and that the effect is most noticeable in systems employing intermediate distributing frames between calling lines and line 40 switches, on account of the fact that in such systems the length of the local test conductors of the lines is much greater, leading to a greater transfer of energy.

A further study of the situation appears to 45 reveal that the transfer of energy from a private normal conductor of a busy line is scarcely noticeable on account of the fact that the private normal conductor of a busy line is grounded, preventing a high tone voltage 50 thereon. Therefore, if tone is kept off the conductors of idle lines the transfer of tone current is prevented for all practical purposes.

The particular arrangement employed to 55 accomplish the foregoing object consists in

the provision of a pair of contacts individual to each line, which are arranged to be closed only when the line is calling. This arrangement is shown in the accompanying drawings as applied to a plunger type lineswitch and 60 the tone applying contacts are controlled by the plunger of the lineswitch so that the tone is disconnected from the local test conductor of the line except when the plunger is in the bank, thereby maintaining the tone disconnected except when the line is a calling line. 65

A further object of the invention which naturally follows from the carrying out of the preceding one, is to limit the time during 70 which the distinctive tone current is flowing, thereby permitting much smaller and more easily maintained sources of tone current to be used.

There are various other objects of the invention which are concerned mostly with the 75 circuit details employed and which will be fully appreciated upon a further perusal of the specification.

Referring now to the accompanying drawings comprising Figs. 1 and 2, 3 and 4, there 80 is shown by means of the usual circuit diagrams a sufficient amount of apparatus in a telephone system embodying the principles of the invention to enable the same to be understood. 85

Fig. 1 shows the lineswitch LS individual to the line of substation A, and the selector E.

Fig. 2 shows the trunk circuit TC which is accessible to the selector E on one level and the associated trunk line comprising conductors 110 and 111 which extends to a distant office and there terminates in the operator's circuit OC. It may be assumed that the operator at the switchboard shown in the drawings is the regular toll recording operator which responds and records the necessary information when the subscriber desires a toll connection. This operator must of course ascertain if the calling subscriber is to be given toll service and certain things about the class in which the calling line is placed. This information is gathered by the operator from listening to the distinctive tone applied from the test conductor of the calling line in a manner to be hereinafter pointed out. 100

Figs. 3 and 4 show modifications of the line switch LS, Fig. 1.

Referring now particularly to Fig. 1, two tone transformers 14 and 15 are shown. It 110

is assumed that the primary windings of these 5 transformers are connected, respectively, to different distinctive tone sources. Two tone 10 transformers are shown in the present case, and as many others may be provided in any 15 particular instance as required.

The invention having been described generally, a detailed description of the operation of the apparatus shown will now be given. 10 For this purpose it will be assumed that the subscriber of substation A, desiring a toll connection, removes his receiver and dials the digit assigned to the toll recording operator. When the receiver is removed at substation A, line relay 12 of the line switch LS energizes over the line conductors 2 and 3 of the calling line and through the resting contacts and armatures 10 and 11 of the combined pull-down and bridge cut-off magnet 20 8. Relay 12 energizes and at armature 13 closes a circuit for the pull-down winding of the magnet 8 including the open main conductor OM controlled by the associated master switch MS. Upon the energization of 25 the pull-down winding, the associated plunger arm 16 is attracted and it forces the plunger into the banks. Also, the armatures 10 and 11 are attracted and they disconnect ground and line relay 12 from the 30 conductors of the calling line. Relay 12, however, being slow acting, maintains its armature 13 attracted for an interval.

The line conductors 2 and 3 of the calling line are now extended to the corresponding 35 conductors 27 and 29 leading to the associated selector E, and the private normal conductor 5 is connected to the corresponding conductor 28, the release trunk conductor of the selector E. Accordingly line relay 35 of 40 the selector E energizes over the calling line and closes at armature 51 a circuit for release relay 36. Release relay 36 energizes and prepares the selector for operation at armature 53 and at armature 52 places ground on the 45 release trunk conductor 28, thereby grounding the private normal conductor 5 of the calling line, which makes the calling line busy in the banks of the connectors having access to it through the terminals 7 and other 50 multiple terminals. As another result of the grounding of release trunk conductor 28, a circuit is closed through the bridge cut-off winding of magnet 8 so as to maintain the armature 16 operated and to maintain the 55 bridge cut-off armatures 10 and 11 attracted after the slow acting relay 12 falls back. It will be noted that tone current from the secondary winding of the transformer 15 may now flow over the private normal conductor 5 of the calling line and over the release 60 trunk conductor 28 of the trunk line leading to the selector E. There is no danger of electrostatic induction taking place to transfer the tone to adjacent conductors, however, 65 owing to the fact that release trunk conduc-

tor 28 is at present grounded at armature 52 in the selector E.

When the calling subscriber operates his calling device in accordance with the digit necessary to trunk the call to the toll recording operator, the circuit of line relay 35 is opened a corresponding number of times. Each time line relay 35 deenergizes in response to one of the interruptions thereby produced, it closes a circuit for vertical magnet 40 as follows: from ground by way of the resting contact of armature 59 and said armature, armature 51 and its resting contact, armature 53 and its working contact, relay 37, and vertical magnet 40 to battery. By the 80 operation of vertical magnet 40, the wipers 61-63, inclusive, are raised opposite the desired level of bank contacts. Relay 37 is energized in series with vertical magnet 40 and, being slow-acting, retains its armature attracted throughout the vertical movement. As a result of the energization of relay 37, a circuit is closed at armature 54 for stepping relay 38 by way of off normal contacts 43 (which close upon the first vertical step) 90 and interrupter contacts 42. Stepping relay 38, upon energizing, closes a locking circuit for itself at armature 55, and at armature 56 prepares a circuit for rotary magnet 41.

At the end of the vertical movement, slow-acting relay 37 deenergizes and completes the circuit of rotary magnet 41 at armature 54. Rotary magnet 41, upon energizing, advances the wipers 61-63, inclusive, into engagement with the first set of bank contacts in 100 the selected level, and, near the end of its stroke, opens the circuit of stepping relay 38 at interrupter contacts 42. Stepping relay 38, upon deenergizing, opens the circuit of rotary magnet 41 at armature 56, whereupon 105 rotary magnet 41 deenergizes also and closes its interrupter contacts again. In case the trunk terminating in the first set of bank contacts is idle, switching relay 39 energizes immediately. Assuming the trunk to be busy, 110 however, switching relay 39 is short-circuited by the ground potential encountered by test wiper 62, and stepping relay 38 energizes from this same ground potential and closes the circuit of rotary magnet 41 again, whereupon 115 the switch wipers are rotated into engagement with the next set of bank contacts. This alternate operation of stepping relay 38 and rotary magnet 41 continues until an idle trunk is reached, which trunk it will be 120 assumed is the one terminating in bank contacts 64-66, inclusive, whereupon switching relay 39, being no longer short-circuited, energizes in series with stepping relay 38. Stepping relay 38, however, does not energize 125 at this time on account of the high resistance of switching relay 39. Switching relay 39, upon energizing, opens a point in the test circuit and prepares the holding circuit at armature 58; disconnects grounds from arma- 130

ture 51 of line relay 35 at armature 59, thereby opening the circuit of release relay 36; and at armature 57 and 60 disconnects conductors 27 and 29 from the windings of line relay 35, 5 and extends them by way of wipers 61 and 63, bank contacts 64 and 66 and trunk conductors 67 and 69 to the windings of line relay 101 of the trunk circuit TC. Line relay 101, upon energizing, closes a circuit for release relay

10 102 at armature 104, whereupon release relay 102 energizes and places ground on release trunk conductor 68 at armature 106, thereby establishing the usual holding circuit for the switching relays of the line switch C and the 15 selector E before the slow acting release relay 36 of the selector E has had time to deenergize.

As a further result of the energization of line relay 101, ground is placed on the lower winding of the marginally adjusted back 20 bridge relay 103 at armature 105, thereby closing a circuit over the inter-office trunk conductors 110 and 111 and through resistance 135 and relay 134 to the toll recording operator's position. Relay 134 energizes over this 25 circuit, but back bridge relay 103 does not energize on account of the high resistance 135. Relay 134, upon energizing, closes at armature 136 a circuit for the answering lamp L, which circuit includes spring 131 of the key K and its lower contact, and spring 133 and its lower contact. The lamp L accordingly becomes lighted to inform the operator of the call.

The operator, upon noting the lighted condition of the lamp L, manipulates her listening key K', thereby connecting her listening taps to the trunk conductors 110 and 111. In order to hear the tone the operator throws the key K in such a direction as to operate springs 131 and 132. Spring 131 disconnects the lamp L and prepares another circuit for it and spring 132 places a shunt around the high resistance 135, whereupon the marginally adjusted back bridge relay 103 of the trunk circuit TC energizes and at armature 107 40 shifts the release trunk conductor 68 from ground at the normally closed contacts controlled by armature 107 to ground through the primary winding of the induction coil 109. At armature 108, relay 103 places a bridge across the outgoing trunk conductors including the secondary winding of the tone 45 transformer 109, and the associated conductor in series. By this operation the tone current flowing in conductor 68 passes to the talking conductors and is heard by the operator.

After the operator has noted the class of the calling line, she throws the key K to the opposite position, thereby restoring the springs 131 and 132 and operating spring 133. 50 Spring 133 takes over the function of spring 131, and spring 132 reinserts the resistance 135 in the circuit, whereupon the marginal back bridge relay 103 in the trunk circuit TC restores and disconnects the primary winding 55 of the transformer 109 from the release trunk

conductor 68, at the same time applying the original ground source to the release trunk conductor. It may be noted that armature 108 disconnects the secondary winding of the tone transformer from across the talking conductor so as to prevent unnecessary shunting of the talking current at this point during conversation. 70

The operator may now converse with the calling subscriber and learn his wants and make the necessary ticket to pass to the toll operator, provided of course that the calling line is entitled to the class of service desired. 75

When the receiver is replaced at substation A after the conversation with the toll recording operator is terminated, line relay 101 of the trunk circuit TC deenergizes and opens the circuit of relay 134 of the operator's circuit OC. Relay 134 thereupon deenergizes and completes a circuit for the lamp L which 80 includes the upper contact of spring 133 of the key K and said spring, lower contact of spring 131 and said spring, and armature 136 and its resting contact. 85

The operator, upon noting the lighted condition of the lamp L, knows that the calling subscriber has now replaced his receiver and she accordingly restores the key K. 90

As a further result of the deenergization of line relay 101 of the trunk circuit TC, the circuit of release relay 102 is opened at armature 104. Release relay 102, upon deenergizing, removes ground from release trunk conductor 68 at armature 106, whereupon magnet 8 of the line switch LS and the switching relay of selector E, Fig. 1, deenergize. The deenergization of magnet 8 of the line switch LS results in the restoration of the circuit conditions in the line switch to normal, and the deenergization of switching relay 39 of the selector E results in a circuit being closed at armature 59 and through armature 51 and its resting contact, armature 53 and its resting contact, and off normal contacts 45 for release magnet 44. Release 100 magnet 44 thereupon energizes and the wipers of the switch E are restored to normal position in the usual manner, whereupon the circuit of release magnet 44 is opened at off 105 normal contacts 45. 110

From the above it will be seen how the operator is enabled to listen to the tone placed on the line of substation A at the exchange in accordance with the class thereof. It is perfectly obvious if the line of substation A is later changed to another class, the appropriate tone connection may be made, or tone may be eliminated entirely, depending upon the class to which the line is changed. 120

When the line of substation A is called 125 through the terminals 7, the placing of ground potential on the private normal conductor 5 results in the energization of the B. C. O. winding of the magnet 8 and in the operation of the bridge-cut-off arma- 130

tures 10 and 11, but the plunger arm is not operated as is well known. Therefore, the tone source is not connected up.

In case it is desired to have the tone source connected up when the line is called, as well as when calling, the conductors connected to spring 9 and its associated contact are removed and connected to a pair of normally open springs in the same assembly as the B. C. O. armature springs 10 and 11. Fig. 3 shows how the connections are made. Another modification is shown in Fig. 4. Referring to this latter figure, if it is desired to have the tone connected up only when the line is called, spring 9 may be provided with a normally engaging contact spring, and the contact pair so formed are connected in series with the above mentioned normally open springs in the B. C. O. assembly.

20. What is claimed is:

1. In a telephone system, telephone lines of different character, a local conductor for each line, tone sources of different character, and automatic line switches adapted when actuated by calling lines to connect their local conductors to the corresponding tone sources, and when released to disconnect said local conductors.

2. In a telephone system, telephone lines of different character, a local conductor for each line, tone sources of different character for said lines, and plunger line switches having contacts actuated by the movement of the plungers when actuated by calling lines to connect their local conductors to the corresponding tone sources, and released to disconnect said local conductors.

3. In a telephone system, telephone lines, a central office wherein said lines terminate, local conductors therefor at said central office, calling and called terminals for said local conductors, an intermediate distributing frame for facilitating interconnection of said terminals, a tone source at the central office, and means actuated on originating calls only for applying tone current to the local conductors.

4. In a telephone system, telephone lines, a central office wherein said lines terminate, local conductors therefor at said central office, calling and called terminals for said local conductors, an intermediate distributing frame for facilitating interconnection of said terminals, a tone source at the central office, trunk lines, automatic switches for extending calling lines to said trunks, and means controlled

by said automatic switches for applying tone current to the local conductors.

5. In a telephone system, telephone lines, line relays for said lines, a central office wherein said lines terminate, local conductors for said lines at said central office, calling and called terminals for said local conductors, a tone source at the central office, trunk lines, line switches for said telephone lines, means for actuating said line switch upon the energization of the line relays on originating calls to extend the lines to idle trunks and to connect the local conductors thereof to said tone source, and means actuated by the closure of called lines for disconnecting their line relays without connecting said source to the called line local conductors.

6. In a telephone system, telephone lines of different character, means by which an operator can answer calls from any of said lines, means for indicating to the operator the character of the calling line including an identifying circuit for connection with apparatus individual to said lines, and means for closing said circuit only on originating calls.

7. In a telephone system, telephone lines of different character, means whereby an operator may answer calls from any of said lines, means for indicating to the operator the character of the calling line including a tone source for connection with the sleeves of the lines, and means for applying the current from said source to said sleeve on originating calls only and for preventing said tone current from standing on the sleeves when the lines are idle.

8. In a telephone system, telephone lines of different character, an individual line switch including a local conductor for each line, a tone source for certain of said lines, and means actuated responsive to either an incoming or outgoing call over one of said lines for connecting its local conductor to said source.

9. In a telephone system, telephone lines of different character, an individual line switch including a local conductor for each line, a tone source for certain of said lines, and means individual to one of said lines actuated in case the line is called for connecting its local conductor to said source.

In witness whereof, I hereunto subscribe my name this 16th day of February, A. D., 1926.

TALBOT G. MARTIN.
